US00D891619S

(12) **United States Design Patent** (10) Patent No.: **US D891,619 S**
(45) Date of Patent: **** Jul. 28, 2020**

(54) **BONE PLATE FEATURES**

- (71) Applicant: **CROSSROADS EXTREMITY SYSTEMS, LLC**, Memphis, TN (US)
- (72) Inventors: **Michael Chad Hollis**, Collierville, TN (US); **Daniel Sayer**, Southaven, MS (US)
- (73) Assignee: **CROSSROADS EXTREMITY SYSTEMS, LLC**, Memphis, TN (US)
- (**) Term: **15 Years**
- (21) Appl. No.: **29/711,465**
- (22) Filed: **Oct. 31, 2019**
